UNITED STATES PATENT OFFICE.

GERALD DEAKIN, OF BERKELEY, CALIFORNIA.

AUTOMATIC TELEPHONE-EXCHANGE SYSTEM.

1,164,479.

Specification of Letters Patent. Patented Dec. 14, 1915.

Application filed October 26, 1911. Serial No. 656,912.

To all whom it may concern:

Be it known that I, GERALD DEAKIN, a citizen of the United States of America, and a resident of Berkeley, Alameda county, California, have invented a new and useful Improvement in Automatic Telephone-Exchange Systems, of which the following is a specification.

My invention pertains to an improved electrical circuit for a switch adapted to establish automatically, connections between subscribers in a telephone exchange system. At the present time the switches commonly used in extending and completing connec-

tions in automatic telephone systems are divided into two general classes. In the first class are those switches adapted to extend or trunk the connection from the terminus of the calling subscriber's line to the next

switch which switch either completes the connection or extends it to another similar switch, to be further extended or trunked. These trunking switches are commonly known as "selectors." In the second class

are those switches adapted to complete the final step in the connection between the calling and the called subscriber's line. This form of switch is adapted to supply current for supervision, transmission of speech and for the ringing of the called bell at the called station and is commonly known as a "connector."

The object of my improved electrical circuit is to combine in one switch the functions of the "selector" and of the "connector" so that the same switch may be used to extend or complete a connection, as occasion demands.

My improved electrical circuit applies to no particular form or design of switch from a mechanical viewpoint, but may be applied to any switch whose parts permit of adaptation to my circuit.

As before stated, in the automatic telephone systems now in general use, a "connector" completes the connection between the calling subscriber's line and called subscriber's line while a "selector" establishes automatically, the connection between the terminus of the calling subscriber's line and the proper connector. Connectors are usually arranged to make connection with any one of a group of 100 lines. Thus in a telephone exchange system not exceeding one hundred (100) lines, the connection between the called and calling line may be made by

a connector without the aid of a selector. Where the number of lines in an exchange system exceeds one hundred (100) but not one thousand (1000) a selector must first be used by the calling subscriber to select the particular group of connectors serving the particular group of 100 lines containing the desired number. When the capacity of a system reaches ten thousand (10,000) lines, an additional selector must be used to select the particular 1000 in which the number of the called party lies. In other words, an additional selector is required whenever a digit is added to the telephone number.

In any large exchange system there are always groups of stations between which stations in such a group the rate of calling is very high as compared with the rate of calling to the stations outside of the group. These groups include local private exchange systems and for the most part do not exceed 90 or 100 stations in capacity. In such groups as these, it is very desirable that local intercommunication be afforded by a means involving the calling of two digits only. It is also necessary that the subscribers in each group be able to call any other subscriber forming part of the main exchange system. My improved electrical circuit provides for this. A switch so arranged will complete a local connection directly as would a connector of the usual type, but when establishing a connection with a subscriber outside of the group with which it is associated, will act as a selector and will afford the means of trunking or extending the call to the next trunking switch or connector as the case may be.

In my improved circuit I provide a means for restricting any local station to local service, exclusively, thus making it impossible for a local station so restricted to effect a connection with a subscriber outside of its particular group. I also provide for a means for registering the number of completed calls made to subscribers outside of the group in which the call originates.

In the preferred form of my invention I arrange the switch so that it normally operates as a connector, and is converted into a selector when a pre-determined number or row is called. For example: In a connector arranged for 100 lines in ten rows of ten each, the tenth row of line contacts selected when the digit 0 is called would be so arranged as to cause the circuit of the switch

to be changed from that of a connector to that of a selector. Where desirable this upper row would afford a choice of a plurality of trunks, to a central office, the switch 5 when converted into a selector being arranged to rotate or otherwise select the first idle outgoing trunk.

For the sake of clearness I will make use of, in describing my invention, switches of 10 the general physical form described in United States Patent No. 815321, granted to Messrs. A. E. Keith, John and C. J. Erickson, on March 18, 1906.

In the accompanying drawings, Figure 1 15 illustrates my improved combination "connector" and "selector" circuit; also an associated subscriber's line and telephone circuit. In Fig. 2 is shown a skeleton outline of a second subscriber's line and telephone circuit. In Fig. 3 is shown a skeleton outline of a 20 second subscriber's line and telephone circuit. In Fig. 3^a are shown two trunk line conductors terminating on a bridged relay of a "selector" or other switch at a main exchange. In Fig. 3^a is shown a bridged relay having its battery connections reversed so 25 as to cause current to flow in the opposite direction in the calling line, for a purpose hereinafter referred to.

At A in Fig. 1, is shown a simple form 30 of subscriber's station telephone circuit consisting of a transmitter, receiver, ringer, condenser, switchhook and at 3 contact springs controlled by the calling dial and adapted to open the line circuit intermittently when in operation. V, P and R represent the subscriber's line contacts, which are adapted to be engaged in electrical connection by the switch wipers, VW, PW and RW respectively. 17, 18, 19, 20 and 21 represent "side switches" controlled by the electro-magnet 35 PM, each side switch being arranged to make alternately three connections, indicated by the side switch number suffixed by the letters a, b and c. D represents a cut off relay adapted to remove the switch from connection 40 with the subscriber's line on calls incoming to the subscriber's station, A. G represents the controlling winding of a service meter connected serially in one side of the subscriber's line. VM and RM represent 45 electro-magnets controlling the vertical and rotary motion of the switch respectively. J represents the "release" electro-magnet and is controlled by the shaft contact 30, and the slow-acting relay L. Shaft contact 30 is arranged to close whenever the shaft of the 50 switch to which wipers VW, RW and PW are fastened, is out of its normal position. K represents a line relay controlling the operation of the "vertical" and "rotary" magnets VM and RM respectively, through slow-acting relays L and M. H and S represent 55 relays controlled by shaft contact springs 31 and 33. These relays when energized, are arranged to convert the electrical circuit of 60 the switch from a circuit adapted to the

establishment of local connections as done by a "connector" to a circuit adapted to trunk calls to other switches, as is done by a "selector". Contact spring 31 is adapted to make and break the contacts shown when a 70 particular number is called. In one form of my invention it engages a fixed projection on the shaft and is moved only when the shaft is stepped up to the last row. N represents a retardation coil of high resistance 75 and impedance. E represents a supervisory relay and affords the means of holding the switch busy during trunked connections. RR represents the "ringing" relay controlling swinging springs 66 and 61. Q represents the called line relay. F represents a relay adapted to give the calling subscriber a "busy" signal should the line called be busy. Relay I operates as an interrupter on trunk connections and causes the rotary 80 magnet RM to rotate the wipers over busy trunk contacts. 39 and 40 represent condensers. 64 and 63 represent contact springs controlled by the private magnet PM.

In Fig. 2, V', P' and R' represent line 90 contacts of a second subscriber's line adapted to be engaged by wipers VW, PW and RW, Fig. 1, respectively. D' represents a cut off relay similar to that shown at D in Fig. 1. At B is shown a simple form of 95 subscriber's station telephone circuit such as is shown at A in Fig. 1.

In Fig. 3, V'', P'' and R'' represent line contacts of a trunk terminating at a main office on a bridged relay, C. The line contacts are adapted to be engaged by wipers VW, PW and RW, Fig. 1, respectively. The contacts V'', P'' and R'' of the trunk lines are in the same group with the corresponding contacts V', P' and R', respectively, of the subscribers' lines, that is, there are three groups, each comprising several single rows of contacts, namely, a group of tip contacts including V' and V'', a group of test contacts including P' and P'' and a group of 105 sleeve contacts including R' and R''.

Each of the side switches previously referred to consist of a movable contact spring and three fixed contacts, the whole being controlled by the electro-magnet PM, Fig. 1, 115 and so designed that the side switches are normally held in what is called their first or normal position under the tension of a spring or springs which tend to force them into their second and third positions. The 120 electro-magnet, PM, when first energized and then deenergized, operates an escapement, causing the side switches to step from their first or normal position into their second position. In other words, the movable 125 springs are caused to break connection with the first series of fixed contacts and make connection with the second series of fixed contacts. When the private magnet is energized and deenergized a second time, it 130

causes the side switches to step from their second into their third or final position. The side switches are caused to resume their normal position by the energizing of the release magnet L, which magnet in addition to forcing the side switches back into their normal position, releases the switch shaft to which the wipers are attached, allowing the shaft to resume its normal position. Contact 10 between springs 63 and 64 is adapted to open whenever electro-magnet PM is energized.

The operation of a switch arranged according to my improved circuit is as follows: We will first consider the case in which one 15 local station desires to establish a connection with another local station. In this case station A, Fig. 1, may be considered as the calling station and station B, Fig. 2 as the called station. To call, the subscriber at station A 20 removes the receiver from the switchhook thereby closing a circuit through his telephone set from earth 1, through battery 2, one winding of K, 37, 60, T^a, 5, conductor T^a of calling line, telephone set at station 25 A including calling device contacts 3, conductor T^a of the calling line, 4, winding of meter controlling winding G, 13, 12, the other winding of K to earth again at 1. Current flows through this closed circuit and 30 energizes relay K. Metering apparatus at G does not operate as it is polarized or otherwise arranged to operate only when current flows through the line in the reverse direction. The operation of relay K energizes 35 relay L, a circuit being closed from 1, through 28, 27, winding of L, 2 to 1. The switch remains in this condition until the calling dial at station A is operated. This dial, when operated, rapidly 40 opens and closes the line circuit at 3. The number of times the line circuit is opened depends upon the digit called on the dial. For example, if digit 5 is called, the circuit is broken 5 times. The speed of these interruptions is so adjusted as to permit relay K 45 to follow them, but not the sluggish relays L and M. In this way a circuit is closed at each interruption from 1, through 28, 29, 25, 24, winding of M, winding of VM, 17^a, 17, 50 2 to 1. The closing of this circuit energizes relay M, also the "vertical" magnet VM, thereby causing the switch to step up one row or unit. At each of the succeeding 55 openings of the line circuit at 3, the vertical magnet, VM, is caused to step the shaft up one additional row or unit. Following the cessation of the series of interruptions, the line circuit remains closed through contact 3. Relays K and L remain energized. Relay M due to its sluggish action did not resume 60 its normal position during the operation of the dial, but does so now, its circuit being open between 28 and 29. Relay M when first energized, as previously stated, 65 energizes the electro-magnet PM, a circuit

being established from 1 through 31, 68, 43, 42, winding of PM, 2 to 1. As previously stated, electro-magnet PM controls the side switches and when deenergized after being energized causes them to step into their next 70 position. Therefore, when contact is broken between springs 42 and 43, which occurs when relay M is deenergized, the electro-magnet PM is also deenergized and allows side switches to step into their second position, causing 17, to break contact with 17^a, and make contact with 17^b; likewise 18, 19, 20 and 21 break contact with 18^a, 19^a, 20^a and 21^a respectively and make contact with 18^b, 19^b, 20^b and 21^b respectively. 75

When the dial is operated a second time, relays K and M again operate as described in the preceding paragraph, this time, however; the "rotary" magnet RM, is energized instead of the vertical magnet VM, a circuit 80 being established from 1, through 28, 29, 25, 24, winding of M, 52, 53, 6, 7, winding of RM, 17^b, 17, 2 to 1. The switch shaft is rotated one step each time the magnet RM 85 is energized. If the proper digits have 90 been called the switch wipers VW, PW and RW will upon the cessation of the second series of impulses, be in electrical contact with the called line terminal V', P', and R', respectively. The private magnet PM 95 is again energized at the beginning of the second series of impulses and when deenergized, causes all side switches to step into their third position, thus connecting 17 to 17^c, 18 to 18^c, 19 to 19^c, 20 to 20^c and 21 to 21^c. When side switch 20 steps into its 100 third position, wiper PW is grounded. In this way relay D' is energized, thereby removing a switch similar to that shown in Fig. 1, from connection with called line, 105 as shown in Fig. 2. A circuit is established from 1, Fig. 1, through 20^c, 20, PW, P', winding of D', 2 to 1. The grounding of wiper PW in addition to operating cut off relay D' makes the called line Fig. 2, busy 110 to all other switches, as hereinafter described. Side switch 21 places a ground on contact P, thus making the calling line busy to all other switches. The contact made between 17 and 17^c causes the ringing delay 115 RR to send out intermittently over the called line, an alternating or pulsating current from "ringing" generator Y, thereby causing the ringer at station B to ring at intervals. To accomplish the above result 120 a closed circuit is intermittently established from earth 1, through interrupter W, 44, 45, winding of RR, 17^c, 17, 2 to 1. Whenever relay RR is energized spring 61 breaks contact with 62 and makes contact with 60 125 and spring 66 breaks contact with 67 and makes contact with 65 thereby causing current to flow from one pole of ringing generator Y, through 60, 61, 9, 10, VW, V', one side of called line, ringer and condenser 130

at station B, opposite side of the called line, R', RW, 19^a, 19, 66, 65 to the other pole of generator Y. During the intervals the local circuit is open at interrupter W 5 relay RR is in its normal position, thus when the called subscriber answers, a circuit permitting the flow of a direct current is closed through the telephone set at station B. A direct current is now caused to 10 flow from 1, through one winding of Q, 64, 63, 62, 61, 9, 10, VW, V', telephone set at station B, R', RW, 19^c, 19, 66, 67, 51, 50, the other winding of Q, 2 to 1. Relay Q is now energized and locks up during the 15 remainder of the connection, a circuit being established from 1, through one winding of Q, retardation coil N, 18^a, 18, 46, 47 the other winding of Q, 2 to 1. The operation of relay Q opens the circuit of relay RR 20 between contacts 44 and 45. This latter relay therefore remains in the normal position during the remainder of the connection. The calling subscriber at station A and the called subscriber at station B are now in 25 communication with each other. At the end of the conversation, the connection is released by the hanging up of the calling subscriber at station A. The disconnection is caused by the opening of the line circuit 30 at A, thus deenergizing relay K, which in turn releases slow-acting relay L, thus energizing the release magnet J, current flowing from 1, through 28, 29, 25, 26, winding of J, shaft contact 30, 2 to 1. The switch now 35 resumes its normal position and opens the release circuit at 30.

The preceding paragraphs describe the method of operation of the switch when establishing a connection with a non-busy line. 40 Should the called line be busy, the operation of the switch is the same as previously described, up to the point where the wipers engage the line contacts of the called line with the side switches in the second position. 45 It should be noted that contact P' in the line terminals of a busy line is connected to earth 1, through wiper PW of the engaging switch in case the busy line is the called line, or through side switch 21 in case the busy 50 line is the calling line. Therefore, whenever a switch, Fig. 1, selects the contacts of a busy line and the side switches are in the second position, a circuit is established from grounded contacts P', Fig. 2, through PW, Fig. 1, 55 20, 20^b, 56, 55, winding of F, 41, 42, winding of PM, 2 to 1. The result is that relay F is energized and locks up, a circuit being established from earth 1, through 23, 22, 54, 55, winding of F, 41, 42, PM, 2 to 1. This closed 60 circuit, in addition to energizing relay F, also keeps energized the electro-magnet PM, which, as before stated, controls the side switches and local contacts 64 and 63. The result is that the talking circuit connecting 65 the calling line with the wipers VW and

RW, remains open at side switch 19 and between contacts 63 and 64. The calling line is therefore not placed in connection with the called line. To indicate to the calling subscriber that the called line is busy, a "busy tone" is placed on the calling line by the closing of contacts 57 and 58 on relay F, a circuit being established from a grounded "busy tone" transformer through conductor 70', 57, 58, 19^b, 19, 66, 67, 39, T³, 5 T², subscribers' 75 telephone set at station A, 3, T¹, 4, winding of G, 13, 12, one winding of K, to earth again at 1. Upon the receipt of the busy tone the calling subscriber hangs up his receiver, thus opening the calling line circuit at station A 80 and allowing the switch to release as previously described. It should be said that following the cessation of the second series of interruptions, relay M resumes its normal position, as previously described. Prior to 85 this relay M energized electro-magnet PM, current flowing from 1 through 31, 68, 43, 42, winding of PM, 2 to 1. Springs 41, 42 and 43 are so adjusted as to cause contact to make between springs 41 and 42 before contact is 90 broken between springs 42 and 43. Therefore, when wiper PW engages line contact P' when grounded, as is the case when the called line is busy, the circuit through the electro-magnet PM is not broken when relay 95 M resumes its normal position, but remains closed in series with relay F as previously described.

What has been said thus far applies for the most part to a switch arranged in accordance with my improved circuit and operated as a connector in completing or attempting to complete directly, a connection between two local stations. My improved circuit, as previously stated, also permits the trunking or extending of a call to other switches for the ultimate connection with a distant subscriber. In the preferred form of my invention, the switch is so arranged that when a particular number or digit is called, spring 100 31 breaks contact with spring 68 and makes contact with springs 32 and 33. This contact spring 31, may be operated by any part of the switch which changes its position, in accordance with the dial interruptions originating at the calling station. We will assume that the tenth or top row of line contacts is reserved for trunks to a central office. In this case the shaft contacts will be operated when the digit "0" is called. This digit 105 110 115 120 125 130 135 is called, this digit when called, interrupts the line circuit ten times, thus causing the switch shaft to step up ten rows or units, which in the present form of commercial switches, is the top row. The line contacts in this top row can be connected by trunk lines to a central office. Each trunk line will terminate in the central office on a bridged relay forming part of some switch, as shown in Fig. 3. The function of this relay is to extend or complete the

call in response to impulses originating at the calling station and passing through the switch shown in Fig. 1.

- Assume station A desires to make a trunk connection through a central office with the trunk line contacts arranged as just described. The operation of the switch during the calling of the digit "0" is the same as described in the preceding paragraphs.
- The movement, however, shaft spring 31 breaks contact with spring 68 and makes contact with 32 and 33, the following changes take place in the circuit of the switch. The windings of relays K and Q are removed from connection with the calling line by the opening of contact between 37 and 60, 50 and 51, 12 and 13 and 9 and 10. Relay E, by the closing of contact between 51 and 69, is placed in series with one side of the calling line. Wiper VW is placed in direct metallic contact with the calling line by the closing of contact between 10 and 11. Contact is made between 7 and 8 and broken between 6 and 7 thus removing the rotary magnet RM, from the control of line relay K and placing it in series with interrupter I, the function of which is to cause the switch to rotate until a non-busy trunk is selected, after which the side switches step into their second position, opening the circuit of the rotary magnet, thus preventing the further rotation of the switch. This action of the rotary magnet is accomplished in detail as follows: The closing of contact between 7 and 8 energizes interrupter I and rotary magnet RM, a circuit being established from 1, through 16, winding of I, 8, 7, winding of RM, 17^b, 17 2 to 1. The switch rotates one step, then the circuit opens between 14 and 16, thus de-energizing both interrupter I and electromagnet RM and arranging them for a second operation. The switch is prevented from releasing during its rotation by the contact or series of contacts made between springs 14 and 15 on interrupter I. The circuit thus closed energizes slow-acting relay L which being sluggish in operation, does not chatter during the interruptions.
- At the beginning of the call relay M is energized and in turn energizes the private magnet PM. At the end of the first series of interruptions, relay M resumes its normal position, thus de-energizing the private magnet PM, all as previously described. The closing of the circuit through interrupter I, causes the rotary magnet RM, to operate the moment the side switches step into their second position, which occurs when private magnet PM is de-energized. Following the first operation of the rotary magnet RM, the private magnet PM is again energized a circuit being established from 1, through 70, 71, winding of PM, 2 to 1.
- Should the first trunk be busy, contact P'' will be found grounded, as previously described. A circuit is thus established from grounded contact P'' through PW, 20, 20^b, 48, 49, this latter contact being closed by the operation of relay S, winding of PM, 70 2 to 1. In this way the private magnet is sustained as long as wiper PW passes over busy contacts. The moment, however, a non-grounded contact P'' is selected, the circuit through the private magnet PM is 75 opened. The private magnet thus becomes de-energized and allows all side switches to step into their third position, thereby opening circuit of the rotary magnet RM, between 17 and 17^b. The circuit of the switch 80 now affords a clear pair of wires from the calling station A to the trunk switch Fig. 3, and current flows from earth 1, Fig. 3, through one winding of C, R'', RW, Fig. 1, 19^a, 19, 66, 67, 51, 69, winding of E, T^a, 5, 85 T^b, telephone set at A, including calling device contact 3, T¹, 4, winding of G, 11, 10, VW, V'', Fig. 3, the other winding of relay C, 2 to 1. Relay E now operates and holds the switch busy, a circuit being established 90 from earth 1, through 34, 35, winding of L, 2 to 1. As before stated, relay L when energized, opens a release circuit between contacts 25 and 26. The circuit now described will permit of indefinitely extending a call. 95
- The interruptions from station A in operating the distant switches may cause relay E to chatter but not the sluggish relay L. Therefore, the switch circuit will remain unchanged until the permanent opening of 100 the line circuit at the calling station A. When this occurs, relay E resumes its normal position, thereby allowing relay L to fall back and close the release circuit. The release of the distant trunking switches is 105 effected by the de-energizing of relay C, Fig. 3 or its equivalent, which, as before indicated, is also under the direct control of the calling station.
- The meter controlling mechanism G in 110 series with the calling line as before stated, does not operate when the direction of current flow in the calling line is as shown in Fig. 1 and Fig. 3. To operate the meter, the distant trunking apparatus is so arranged that when the called subscriber answers, the direction of current flow in the calling line is reversed. In other words, the relay fulfilling the function of relay C and shown as C' in Fig. 3^a, has its battery connections reversed so as to cause the current to flow in the opposite direction in the calling line. The manner in which the direction of current flow is reversed is immaterial as it forms no part of my invention. Any 115 of the well known methods of current reversing may be employed in this connection.
- To restrict local stations to the making of local calls only, one side of the calling line is connected to conductor T⁴ instead of T³, 120 125 130

Fig. 1. Thus when an attempt is made to establish a trunk connection, the calling line circuit is opened between contacts 37 and 60, thereby causing the switch to release substantially as previously described.

Having thus described my invention, what I claim and desire to secure by United States Letters Patent, is:

1. In a telephone exchange system, a switching device having primary movement and secondary movement, directive controlling means for the primary and secondary movements, automatic controlling means for the secondary movement, and means adapted upon a predetermined extension of the primary movement to disconnect said directive controlling means and operatively connect said automatic controlling means.
2. In a telephone exchange system, a switching device adapted to connect with a plurality of circuits and having primary and secondary movement, directive controlling means for said primary and secondary movements together with automatic controlling means for said secondary movement, means adapted upon a predetermined extension of the primary movement to disconnect said directive controlling means and operatively connect said automatic controlling means, and means adapted upon the connection of said switching device with an idle circuit to disable said automatic controlling means.
3. In a telephone exchange system, a connector switch provided with a plurality of contacts arranged in rows and a movable contact member adapted to be moved into a position opposite any one of the rows and thereafter to be moved into engagement with any contact in said row, directive controlling means for both movements of the movable contact, automatic controlling means for the latter movement normally ineffective, and means automatically actuated upon the movement of the movable contact member into a position opposite a predetermined row to disable said directive controlling means and render said automatic controlling means effective.
4. In a telephone exchange system, a plurality of subscribers' lines having restricted service, a plurality of subscribers' lines having unrestricted service, a plurality of trunk lines, switching mechanism operated over said subscribers' lines to extend connection between any two of said subscribers' lines and from any one of said subscribers' lines having unrestricted service to a trunk line, but not to extend connection from a subscriber's line having restricted service to a trunk line.
5. In a telephone exchange system, a plurality of subscribers' lines having restricted service, a plurality of subscribers' lines having unrestricted service, a plurality of trunk

lines, switching mechanism operated by impulses sent over the subscribers' lines to connect said subscribers' lines to each other and to a trunk line, and means actuated upon the sending of a predetermined number of said impulses over a subscriber's line having restricted service to disable said switching means, whereby the subscribers' lines having restricted service are prevented from connection with trunk lines.

6. In a telephone exchange system, a switching device normally in a disconnected position and having primary and secondary movement for making connections, with directive controlling means therefor, and means adapted upon a predetermined extension of the primary movement to disable said controlling means and restore the switching device to its normally disconnected position.

7. In a telephone exchange system, the combination of a calling line, a plurality of called lines, a plurality of trunk lines, an automatic switch, means to cause said switch to operate and establish connection between said calling line and any one of said called lines of a local group by the calling of two digits only, means to cause said switch to operate and establish connection between said calling line and any one of said trunk lines, and means individual to the switch adapted to complete the connection of said switch with an idle trunk line by the calling of a single digit.

8. In a telephone exchange system, the combination of a calling line, a plurality of called lines, a plurality of trunk lines, an automatic switch, means to make said trunk lines and said called lines, when in use, "busy" to said switch, means to cause said switch to operate and establish connections between said calling line and any one of said called lines of a local group on the calling of two digits only, means to cause said switch to operate and establish connections between said calling line and the first non-busy trunk line, means for registering the number of completed calls made to subscribers outside of said local group in which the call originates, means to cause the connection of said switch with an idle trunk line by the calling of a single digit, and means of preventing the establishment of a connection between said calling line and any one of said trunk lines.

9. In a telephone exchange system, the combination of an unrestricted calling line, a restricted calling line, a plurality of called lines, a plurality of trunk lines, an automatic switch, a means of causing said switch to operate as a "connector" and establish connections between either of said calling lines and any one of said called lines, a means of causing said switch to operate as a "selector" and establish connections between said un-

restricted calling line and any one of said trunk lines, and a means of preventing said switch from establishing a connection between said restricted calling line and any one of said trunk lines.

- 5 10. In a telephone exchange system, the combination of an unrestricted calling line, a restricted calling line, a plurality of called lines, a plurality of trunk lines, an automatic switch, means to cause said switch to operate as a "connector" and establish connections between either of said calling lines and any one of said called lines of a local group by the calling of two digits only, means to cause 15 said switches to operate as a "selector" and establish connections between said unrestricted calling line and any one of said trunk lines, means for preventing said switch from establishing a connection between said 20 restricted calling line and any one of said trunk lines, and means to cause the connection of said switch with an idle trunk line by the calling of a single digit.

- 25 11. In a telephone exchange system, the combination of a calling line, a plurality of called lines, a plurality of trunk lines, an automatic switch having primary and secondary movement, means to cause said switch to operate as a "connector" and establish connections between said calling line and any one of said 30 trunk lines, relays adapted when energized to change the circuit of the switch from a circuit adapted to the establishment of said local connections to a circuit adapted to trunk calls to other automatic switches, as 35 when the switch operates as a "selector," and means operable in the primary movement of said switch for controlling said relays.

- 40 45 12. In a telephone exchange system, the combination of a calling line, a plurality of called lines, a plurality of trunk lines, an automatic switch, means to cause said switch to operate as a "connector" and establish connections between said calling line and any one of said 50 trunk lines, relays adapted when energized to change the circuit of the switch from a circuit adapted to the establishment of said local connections to a circuit adapted to trunk calls to other switches, as when the switch operates as a "selector," shift contact 55 60 65 springs adapted to control said relays, means for preventing the establishment of a connection between said calling line and any one of said trunk lines, and a train of relays connected to said calling line branch of said switch and adapted to hold said switch

busy on connections between said calling line and said called lines.

13. In a telephone exchange system, the combination of a calling line, a plurality of called lines, a plurality of trunk lines, an 70 automatic switch combining the function of a "connector" and a "selector" switch and adapted to establish connections between said calling line and any one of said called lines or said trunk lines, a calling line 75 branch forming part of said switch, a called line branch forming part of said switch, a source of current for operating said switch, a train of relays connected to said calling line branch of said switch and adapted to hold said switch busy on connections between said calling line and said called lines, a means of removing said train of relays from connection with said switch on connections between said calling line and said 80 trunk lines and in place thereof, inserting in series with said calling and called line branches of said switch, said calling line, said trunk line and said source of current, and another relay adapted to hold said 85 switch busy substantially as shown and described.

14. In a telephone exchange system, the combination of a calling line, a plurality of called lines, a plurality of trunk lines, an 90 automatic switch combining the functions of a "connector" and a "selector" switch and adapted to establish connections between said calling line and any of said called lines or said trunk lines, a means at said calling 95 station to cause said switch to establish such connections, a calling line branch forming part of said switch, a called line branch forming part of said switch, a source of current for operating said switch, a train of relays connected to said calling line branch of said switch and controlling the selective powers of said switch as directed by the calling line, and adapted to hold said switch 100 busy on connections between said calling line and said called lines, a means of removing said train of relays from connection with said switch on completed connection between said calling line and said trunk lines and in place thereof, inserting in series with said calling and called line branches of said 105 switch, said calling line, said trunk line and said source of current, and another relay, adapted to hold said switch busy, substantially as shown and described. 110 115 120

15. In a telephone exchange system, a switching mechanism adapted to act both as a connector and a selector, a trunk circuit for said switching mechanism including condensers, and means operable upon the operation of said switching mechanism as a selector to shunt out said condensers, whereby a circuit for direct current is extended through said trunk and said switch to the next succeeding switch. 125 130

16. In a telephone exchange system, automatic switching mechanism having primary and secondary movement, directive controlling means therefor, and automatic means operable upon a predetermined extension of the primary movement to disconnect said controlling means from said switching mechanism and extend the connection of said controlling means to the contacts of said switch,

for the purpose of directly controlling 10 other switches through said contacts.

Signed by me at San Francisco, this 17th day of October, 1911.

GERALD DEAKIN.
